(57) **CLAIM**

The ornamental design for a garage vehicle position indicator, as shown and described.

DESCRIPTION

FIG. 1 is an elevational perspective, viewed from the bottom of the garage vehicle position indicator, showing its ornamental design. A ball-shaped structure (bottom of the figure) is connected to a housing (top of the figure) via means that may vary in length.

FIG. 2 is a view of the design from its longer side; FIG. 3 is a view of the design from its shorter side; and, FIG. 4 is a view of the design from its top side, with the ball-shaped structure positioned directly underneath the housing.
